G. P. LEWIS.
COMBINED VERTICAL RETORT AND GAS GENERATOR APPARATUS,
APPLICATION FILED FEB. 13, 1922.

1,430,453.

Patented Sept. 26, 1922.

George Pearce Lewis
Attala & Lewis, Attorneys

UNITED STATES PATENT OFFICE.

GEORGE PEARCE LEWIS, OF LONDON, ENGLAND.

COMBINED VERTICAL RETORT AND GAS-GENERATOR APPARATUS.

Application filed February 13, 1922. Serial No. 536,308.

To all whom it may concern:

Be it known that I, GEORGE PEARCE LEWIS, a subject of the King of Great Britain, residing in London, England, have invented 5 certain new and useful Improvements in Combined Vertical Retort and Gas-Generator Apparatus, of which the following is a specification.

In my co-pending specification Serial No. 10 536,307, filed Feb. 13, 1922, I have described a combined retort and generator for the protective progressive distillation and gasification of solid carbonaceous matters in which the temperature increases gradually from 15 the top downwards, gases rich in condensable hydrocarbons and containing some ammonia being withdrawn from the retort and a producer gas suitable for heating or power purposes being withdrawn from the generator, 20 a portion of the producer gas flowing upward through the retorts.

The producer gas before being used for heating or power purposes was passed through an ammonia recovery plant. 25 The gases from the retorts were led through an oil and ammonia recovery plant before being used for heating or power purposes.

A steam or moisture saturated blast, preferably preheated by the producer gas led away from the generator, might be led into the generator and through distributing passages into the retorts. The flues surrounding the retort might be heated by the producer gas before or after removal of the ammonia.

The fuel was preferably preheated in a supplementary chamber, the moisture and the deleterious gases evolved from the fuel 40 being led into the generator or the retorts or used in any other convenient manner.

Alkalies could be mixed with the raw fuel to improve the quality of the oil distilled and under certain circumstances sawdust 45 and like bodies.

The present invention consists in a modification of the arrangements and apparatus described in this prior specification adapted more particularly for the distillation and 50 gasification of strongly coking coals.

In order to ensure the ready passage of the coke from the retorts to the generator, the retorts are formed as vertical chambers of slightly tapering section, the lower ends 55 of which communicate with a funnel shaped

compartment the lower and smaller end of which is connected by means of mechanically operated valves with the upper end of the generator. Rotating rollers provided with spiked or grooved channels help to convey 60 in known manner the lumps of coke from the retorts to the generator.

The funnel shaped compartment serves as a means for controlling the supply of coke to the generator but is not as in previously 65 known manner provided with a grate surface and admission of air for the combustion of the coke.

Part of the producer gases is led through a pipe or other suitable passage (not shown 70 in the drawings) from the generator to the retort and the flow may be regulated by a valve.

In a slightly modified construction the retorts are separated from and placed by the 75 side of the generator to the hopper chamber of which the coke from the retorts is led by a conveyor.

The generator is preferably provided with a mechanically revolved grate and ash ejecting device.

The series of vertical retorts is preferably arranged in settings of eight retorts communicating with a generator common to all the retorts.

It is found useful in some cases to add to the raw fuel besides the substances stated in the prior specification boric compounds and the alkalies added may advantageously be in the form of crude sodium and potassium 80 salts found native in Chile.

Fig. 1 is a sectional elevation of the retorts and Fig. 2 is a sectional elevation of a modification in which the retort is placed by the side of the generator.

In Fig. 1, the retorts are shown at *a* and the generator at *b*; *c* is a hopper chamber for conveying the coke to the generator, *d* are rotating rollers for facilitating the passage of the coke. Valves *e* operated by 100 levers *f* open and close the passage between the retorts and the generator. *g* is an annular steam and water space for keeping the interior temperature low and for furnishing a supply of steam for the 105 generator and retort.

The generator is shown as supported on three legs *h*.

In the modification shown in Fig. 2 the coke from the retorts *a* is led by a conveyor 110

i into the hopper chamber *j* of the generator *b*.

Having thus described the nature of the said invention and the best means I know 5 of carrying the same into practical effect, I claim:—

1. Apparatus for distilling and gasifying solid carbonaceous matter, said apparatus comprising in combination a vertical retort 10 chamber and a vertical generator, a funnel shaped chamber between the retort and generator through which chamber solid material from the lower end of the retort passes to the upper part of the generator, a valve in 15 said chamber for regulating the passage of said material, means for the continuous introduction of a moisture-saturated blast into the generator, means for the withdrawal of part of the producer gases generated in the 20 generator and means for heating said blast by the producer gas from said generator.

2. Apparatus for distilling and gasifying solid carbonaceous matter, said apparatus comprising in combination a vertical retort 25 chamber and a vertical generator, a conveyor connecting the lower end of said retort and a funnel shaped chamber at the upper end of said generator, means for the continuous introduction of a moisture saturated blast into the generator and means for the withdrawal of part of the producer gases generated in the generator.

3. Apparatus for distilling and gasifying solid carbonaceous matter, said apparatus 30 comprising in combination a vertical generator and a plurality of vertical retorts, a

funnel shaped chamber between said retorts and said generator and means for regulating and facilitating the passage of said solid carbonaceous matter from each retort to 40 the generator.

4. Apparatus for distilling and gasifying solid carbonaceous matter, said apparatus comprising in combination a vertical generator and a plurality of vertical retorts, a 45 funnel shaped chamber between said retorts and said generator, means for regulating and facilitating the passage of said solid carbonaceous matter from each retort to the generator, and an annular water-containing 50 chamber surrounding the lower part of the generator.

5. Apparatus for distilling and gasifying solid carbonaceous matter, comprising in combination a vertical retort chamber and 55 a vertical generator chamber, a funnel-shaped chamber through which the solid material from the lower end of the retort passes to the upper part of the generator, a valve in said funnel-shaped chamber for 60 regulating the passage of said material, a lever for opening and closing said valve, rollers in said funnel-shaped chamber for facilitating the passage of said material, and an annular space containing water surrounding 65 the lower part of the generator.

In testimony whereof I have signed my name to this specification.

GEORGE PEARCE LEWIS.
